UNITED STATES PATENT OFFICE

148,354

DESIGN FOR A MECHANICAL TOY BIRD FIGURE

Herman Herzog, Detroit, Mich.

Application July 19, 1946, Serial No. 131,691

Term of patent 7 years

(Cl. D34—2)

To all whom it may concern:

Be it known that I, Herman Herzog, a citizen of the United States, residing at Detroit, in the county of Wayne and State of Michigan, have invented a new, original, and ornamental Design for a Mechanical Toy Bird Figure, of which the following is a specification, reference being had to the accompanying drawing, forming part thereof.

In the drawing

Fig. 1 is a side view of a mechanical toy bird figure, showing my new design;

Fig. 2 is a front elevation of the same;

Fig. 3 is a top plan view of the same;

Fig. 4 is a plan view of underside of the same; and

Fig. 5 is a section of the body shell taken on a plane indicated by the line 5—5 in Figure 1.

I claim:

The ornamental design for a mechanical toy bird figure, as shown.

HERMAN HERZOG.
